G. A. HANLY

AIR SEAL FLUSHING DEVICE

Filed March 11, 1920

UNITED STATES PATENT OFFICE.

GEORGE A. HANLY, OF ELGIN, ILLINOIS.

AIR-SEAL FLUSHING DEVICE.

Application filed March 11, 1920. Serial No. 365,085.

To all whom it may concern:

Be it known that I, GEORGE A. HANLY, a citizen of the United States, residing in the city of Elgin, county of Kane, and State of Illinois, have invented certain new and useful Improvements in Air-Seal Flushing Devices, of which the following is a specification.

The present improvements relate to devices in which a flow of liquid is controlled by a body of air, forming sealing means, interposed between the liquid body and the discharge orifice. In this connection attention is directed to my U. S. Letters Patent Numbers 1,152,810 and 1,152,811 of September 7, 1915 entitled Pneumatic valve apparatus and Pneumatic valve mechanism respectively, in which I have illustrated, described and claimed devices of the same kind and character as the one herein shown, and have so fully explained the principles involved that the same need to be set forth only briefly herein.

The objects of the present improvements are, first, to constitute the device for automatic discharge and for manual-control discharge at will, thus making the same device available for both uses; secondly, to improve the drainer; thirdly, to provide a simple form of safety catch device for the air-entrappling means whereby it may be operated by hand only after a given and necessary supply of liquid is in the tank; and fourthly, to simplify and reduce cost of construction.

In the accompanying drawings, which form a part of this specification, Figure 1 shows in section a tank adapted to contain a quantity of liquid with the flushing apparatus partly in full lines and partly in medial section; Fig. 2 shows an end elevation of the flushing mechanism, the view being taken on the line 2-2 of Fig. 1; Fig. 3 shows a fragment of the supporting means for the tiltable hood and drainer; Fig. 4 shows a perspective of the hood; Fig. 5 shows a perspective of the drainer; and Fig. 6 shows an enlarged fragment in medial vertical section of the auxiliary liquid supply valve.

Water enters the device through the supply pipe 10 and issues at 11, the flow being controlled by the valve 12 which is operated automatically by the float 13, the valve cutting off the supply when the water line reaches a predetermined hydrostatic head.

The liquid is discharged from the tank

through the pipe 15 projecting upward into the tank. The lower end portion of this pipe is surrounded by a closed pipe 16, in spaced relation, having the discharge opening 17, from which opening a connection is made to the water closet bowl when the device is employed in that use. The pipes 15 and 16 form a trap of well-known construction. A drain plug 18 at the bottom of the trap permits the water to be drawn off when so desired.

Means providing an air seal about the upper opening of the discharge pipe 15 comprises a head 20, which is open throughout its bottom portion and closed at sides, ends and top. In my said patents I show constructions in which a similar hood is pivotally mounted on a frame which swings upward. I find that it is feasible to pivot the hood 20 on a fixed part, as on a pair of spaced-apart rods 21 carried by a supporting plate 22 secured in position by a clamping nut 23, the rods 21 being held on the plate by turned-over portions 24 of the metal, as well seen in Fig. 3.

The rods 21 are carried forward and have vertical extensions 25 forming a support for the operating rod 26, this operating rod being pivotally mounted at 27. The operating rod 26 has a catch at 30 adapted to engage the turned-over flange 31 of the hood 20 and hold the hood in its normally horizontal position at all times except when it is desired to release the same for manually controlled operation. When so released the hood 20 swings into its dotted line position of Fig. 1, whereupon the water passes around the lower edge of the drainer 35 and thence into the opening at the upper end of the pipe 15.

The drainer 35 consists as here shown of a substantially square inverted cup open throughout its bottom and closed at sides and top except for the small hole or several such small holes, as 36, which are not strictly essential but which overcome some objectionable noise when the siphon is broken at the end of the flushing operation. This hood 35 slips upon four upstanding cleats 38, the cleats at one side being well shown in Fig. 3, and is thereby held in place. The principal feature of improvement in the drainer is the extension of its inner pipe 40 to the side wall, well illustrated in Fig. 1, instead of carrying it out the top, as in the second of my said former patents. I find that the

operation is more satisfactory with the present arrangement of this pipe 40 and it enables the top of the hood 20 to be brought closer to the drainer 35.

5 I also provide a safety feature in my present device whereby the operating rod 26 may not be moved to release the hood 20 until the water has attained a sufficient hydrostatic head to provide the desired siphonic 10 action, it being pointed out that if the hood 20 is released before a sufficient head is attained in the tank the siphonic action will not be started. This safety feature provides that when the float 13 shall have reached the 15 desired elevation certain operating parts will have been shifted so that the lever 26 may be moved by rocking the handle 50.

The construction illustrated for effecting safety in this respect include first a crank 20 arm 52 rigidly secured upon the float rod 53, this crank 52 being an extension of the pivot for the float rod and being made rigid thereon by giving it a turn at 54 around the rod 53. A pair of parallel and similar substantially horizontally disposed links 55 each terminating in an eye 56 are held upon the crank pin 57 of the crank 52. At the other ends of the links 55 respectively eyes are turned and through these eyes pass the horizontal extension 65 of the pull rod 59 pivoted upon the bell crank 60 on the shaft 61 to which the handle 50 is secured.

It will be noted from Fig. 1 that the rod 26 is given certain bends at its upper end 35 portion which provide a shoulder at 63 and a notch-like space or opening at 64. It will be clear from Fig. 1 that if the handle shaft 61 is rocked the pull rod 59 will be lifted and that the extension 65 thereof will come into 40 contact with the shoulder 63 on the rod 26, thereby lifting that rod at that end and causing the latch 30 to come away from engagement with the projection 31, thus freeing the hood. On the other hand, when the 45 float 13 is in its dotted line position and the pull rod 59 is thereby moved into its dotted line position, through a shifting of the crank 52 and links 55, the cross rod 65 is in substantially vertical line with the notch or 50 space 64 so that if the handle 50 be now operated the cross rod 55 will not engage any part of the rod 26, but will move upward freely into the notch 64 and the cap or hood 20 will not be released. I have thus shown 55 means partly under the control of the operator and partly under the control of the float 13 or of the rising water in the tank for releasing the hood or cap 20 which imprisons the air about the discharge orifice 60 of the pipe 15 and forms an air seal there.

The construction illustrated is such that when the normal hydrostatic head of liquid in the tank is had there is a perfect equilibrium between the water in the trap 16 and 65 the water in the tank, with a body of air

pocketed between these two bodies of water, and that if additional hydrostatic head be added in the tank it will destroy this equilibrium and cause water to flow through the discharge orifice 17 in the trap, and the flow 70 once being started continues until the tank is drained, whereupon the flow ceases and the tank again fills up. In such case of automatic discharge the hood 20 is not released and does not change its position. 75

In many instances it is desirable to flush closets, urinals or the like periodically, even though there be provided means for manual operation, and there are other instances where manual operation is not desired, but 80 where only the automatic feature is wanted, and it is also usually desirable to regulate the time between flushings. I attain these objects in the present device by means of an auxiliary supply valve, well illustrated 85 in Fig. 6, comprising in simple form a plug 70 threaded into the supply pipe 10, the plug having a threaded tapered hole 71, the plug being provided with a discharge opening 72, there being a valve stem 73 90 threaded into the hole 71, an operating handle 74 being used to turn the valve, and a nut 75 on the stem 73 providing a feature of adjustment and locking means for the valve. According to this construction 95 the discharge hole 72 can be closed or opened to such extent as may be desired, thus providing means for supplying additional water to the tank in regulable quantities after the float shall have cut off the main 100 supply.

In operation the normal rapid supply through the pipe 10 will take place as usual until the normal hydrostatic head is reached, whereupon the additional supply 105 will flow through the discharge hole 72, and the length of time between flushings can be made longer or shorter by varying this auxiliary flow. The taper of the threaded hole 71 provides that when the valve stem 110 73 is turned inward so as to close the hole 72 the stem will become tightened whereby water may not escape around the threads.

While I have illustrated and described these improvements in a highly advantageous and successful form, modifications thereof may be made within the scope of the appended claims without departing from the spirit of the improvements herein set forth. 115

I claim:

1. The combination of a tank adapted to contain a liquid, a discharge pipe having a discharge orifice in said tank, float-controlled means for supplying with a relatively rapid flow a given hydrostatic head of liquid to said tank, means providing an air seal about said discharge orifice for maintaining the liquid in said tank from being discharged through said orifice when 125 130

- at the given hydrostatic head while providing for its discharge at a greater hydrostatic head, and means for supplying with a relatively slow flow additional liquid to
- 5 said tank after the given hydrostatic head has been provided therein.
2. The combination of a tank adapted to contain a liquid, a discharge pipe having a discharge orifice in said tank, float-controlled means for supplying with a relatively rapid flow a given hydrostatic head of liquid to said tank, means providing an air seal about said discharge orifice for maintaining the liquid in said tank from
- 10 being discharged through said orifice when at the given hydrostatic head while providing for its discharge at a higher hydrostatic head, and means for supplying a regulable relatively slow flow of additional liquid to said tank after the given hydrostatic head has been provided therein.
- 15 20
3. The combination of a tank adapted to

contain a liquid, an upwardly-extending discharge pipe having a discharge orifice in said tank, float-controlled means for supplying a given hydrostatic head of liquid to said tank, an inverted cup-like device open at the bottom covering and surrounding, in spaced relation, the open end of the upwardly-extending discharge pipe, an air pipe partly within said cup-like device and having one end portion extending downward through a portion of the discharge pipe and another portion extending through a side wall of the cup-like device near the top thereof, and a movably mounted hood having a top wall substantially close to the top of said cup-like device, and being adapted to pocket a quantity of air about said discharge opening, and means for releasably holding said hood in its air-holding position.

GEORGE A. HANLY.
